PLANT MARKER

Filed Feb. 6, 1930

Paul P. Gredell
INVENTOR

Eugene S. Steiner
ATTORNEY

UNITED STATES PATENT OFFICE

PAUL P. GREDELL, OF QUINCY, ILLINOIS

PLANT MARKER

Application filed February 6, 1930. Serial No. 426,383.

My invention relates to identifying markers for plants, shrubbery, trees and the like and has for its primary object to provide a very simple durable and inexpensive device 5 of this character incorporating a removable inscription bearing portion which will normally be fully protected from the elements.

Another object of the invention is to provide a device of this character which is very 10 neat and attractive in appearance and the compactness of which enables it to be located inconspicuously but easily located when desired.

A still further object of the invention is to 15 provide in a plant marker or the like an inscription bearing portion which will require no special ink or marking means and which will conform to the usual inscription bearing but unprotected markers which are usually 20 associated with plants and shrubbery, so that same may be readily adapted and used in the protecting casing provided by my device.

The invention also resides in certain novel 25 features of construction, combination and arrangement of the various parts and in various modes of operation and use,—all of which will be readily apparent to those skilled in the art upon reference to the accompanying 30 drawings in connection with the description appearing hereinafter.

The drawings illustrate what now appears to be a preferred form of the invention. However, it is to be understood that the inventive concept is capable of other mechanical 35 expressions within the spirit and scope of the subject matter claimed hereinafter.

In the drawings,

Figure 1 is a perspective view of a device 40 embodying my invention;

Figure 2 is a cross sectional view taken on the line 2—2 of Figure 1;

Figure 3 is a group perspective view of the marker and casing;

Figure 4 is a perspective view of the blank and fragment of the rod;

Figure 5 is a perspective view of a slight modification of the casing, and

Figure 6 is a section on the line 6—6 of 50 Figure 5 but showing the marker 7 in place.

Referring specifically to the drawings, wherein the same reference characters have been used to designate the same parts in all views, numeral 1 denotes a preferably sheet metal casing of flat rectangular form which is open at both ends as shown.

As indicated in the drawings the wall 2 of the casing 1 extends beyond the opposite wall 3 and is provided with a curled portion 4 extending inwardly to lie substantially contiguous with the outer surface of the inwardly extending flange 5 of the wall 3 which provides one of the edge walls of the casing 1. The curled portion 4 by reason of the inherent springy nature of the metal stock will maintain a pressure contact with the flange 5 thus providing a keeper channel for the rod 6 which is forced thereinto and clamped in place by the combined spring action of flange 5 and the contiguous portion of curl 4.

The marker 7 is preferably of wood and may be, in a given instance, the identical wooden marker sent with the plant or piece of shrubbery by the florist or nurseryman. The marker 7 as shown has the inscription 8 designating the particular species of plant in a given case,—and as indicated in the drawings, the marker 7 is adapted to be inserted into the upper end of the casing 1.

The end of the marker is engaged between the opposed portions of a clip like finger piece 9 whose ends turn out laterally to provide stop flanges 10 to engage the end of the casing to limit movement of the marker 85 thereinto.

It will be clearly evident from the construction of casing 1 that the walls 2, 3 thereof will embrace the marker 7 to hold it against accidental displacement. Manifestly, the clip 9 can be applied to the ordinary conventional wooden marker, now in use.

One end of the casing 1 may be closed by a flange or tab portion 16 as shown in Figure 6 although this item can be dispensed with particularly where the marker will be located on high ground or well above the surface of the ground.

The construction recited eliminates the ne-

cessity for soldering, it being evident that the marker 7 bears against the edge wall flange 5 to hold the curl 4 contiguous therewith and in gripping engagement with the rod 6. By the same token the rod 6 through curled portion 4 prevents flange 5 from shrinking away from a location to frictionally engage marker 7. As in Figure 5 a substitute rod 6^a may have an attaching wire 14 carried by eye 15 so that the device 1^a 10 may be conveniently attached to trees or bushes.

Having thus described my invention what I claim as new and desire to secure by Letters Patent is:

1. A device of the class described comprising a sheet metal casing open at one end, one wall of said casing having an inturned flange providing an edge wall, the opposite wall of said casing extending beyond said first mentioned wall and being provided with an inwardly curved portion the outer surface of which has a yielding engagement with the outer surface of said flange, a carrier rod insertible in said curled portion and frictionally engaged thereby, and a marker insertible in said casing to said open end and having one edge bearing against said flange.

2. The combination set forth in claim 1 and a combined stop and finger piece carried by one end of said marker and adapted to engage the open end of said casing.

3. The combination set forth in claim 1, and a combined stop and finger piece comprising a clip of U-shaped form adapted to engage one end of said marker and removably carried by the latter.

4. A plant marker comprising a casing, one wall of said casing having an integral inwardly curled keeper portion at one edge, the opposite wall of said casing having an inturned flange inwardly of said curled keeper portion and providing a support therefor, a carrier rod insertible in said keeper portion, and an inscription bearing element insertible in said casing.

5. A plant marker including a casing formed from a sheet metal blank, and providing side and edge walls, one side wall having a rod keeper portion extending beyond the adjacent edge wall, and said extension having a reverted portion engaging said edge wall to reinforce and hold same in place.

In testimony whereof I affix my signature.
PAUL P. GREDELL.
